INFLATABLE DISPLAY FORM

James Henry Burrell, Palmerston North, New Zealand,
assignor to Patent Service Corporation of America,
New York, N.Y., a corporation of New York

Filed Mar. 12, 1969, Ser. No. 16,217

Claims priority, application New Zealand Sept. 16, 1968

Term of patent 14 years

Int. Cl. D20—99

U.S. Cl. D80—8

FIG. 1

FIG. 2

FIG. 3

FIG. 1 is a front elevational view of an inflatable display form showing my new design;

FIG. 2 is a rear elevational view thereof; and

FIG. 3 is an elevational view taken from one side thereof, the opposite side being a mirror image of the side shown.

What I claim is:

The ornamental design for an inflatable display form, substantially as shown and described.
